US00D849584S

(12) United States Design Patent (10) Patent No.: US D849,584 S
 Majeric (45) Date of Patent: * May 28, 2019

(54) FINGER RING

(71) Applicants: PRIMOŽ MAJERIC, Brezovica (SI);
MAJA ROLC MAJERIC, Brezovica (SI)

(72) Inventor: Maja Rolc Majeric, Brezovica (SI)

() Term: 15 Years

(21) Appl. No.: 35/504,118

(22) Filed: Nov. 8, 2017

(80) Hague Agreement Data

Int. Filing Date: Nov. 8, 2017

Int. Reg. No.: DM/098702

Int. Reg. Date: Nov. 8, 2017

Int. Reg. Pub. Date: Dec. 8, 2017

(51) LOC (11) Cl. 11-01

(52) U.S. Cl.

USPC D11/34

(58) Field of Classification Search

USPC D11/1, 26–29, 34–39, 79, 89, 91

CPC A44C 9/0007
